(57) **CLAIM**

The ornamental design for a correction and glue tape dispenser, as shown and described.

DESCRIPTION

FIG. 1 is a top right perspective view of a correction and glue tape dispenser according to the new design;

FIG. 2 is a right elevation view thereof;

FIG. 3 is a left elevation view thereof;

FIG. 4 is a front elevation view thereof;

FIG. 5 is a rear elevation view thereof;

FIG. 6 is a top plan view thereof; and

FIG. 7 is a bottom plan view thereof.

FIG. 8 is a top right perspective view of a second embodiment of a correction and glue tape dispenser according to the design;

FIG. 9 is a right elevation view thereof;

FIG. 10 is a left elevation view thereof;

FIG. 11 is a front elevation view thereof;

FIG. 12 is a rear elevation view thereof;

FIG. 13 is a top plan view thereof; and

FIG. 14 is a bottom plan view thereof.

FIG. 15 is a top right perspective view of a third embodiment of a correction and glue tape dispenser according to the new design;

FIG. 16 is a right elevation view thereof;

FIG. 17 is a left elevation view thereof;

FIG. 18 is a front elevation view thereof;

FIG. 19 is a rear elevation view thereof;

FIG. 20 is a bottom plan view thereof; and

FIG. 21 is a top right perspective view thereof.

The broken lines shown in the drawings form no part of the claimed design.
